UNITED STATES PATENT OFFICE.

CLAUD E. FULLER, OF NEW YORK, N. Y., ASSIGNOR TO NEW YORK BRICK HANDLING CORPORATION, OF NEW YORK, N. Y., A CORPORATION OF NEW YORK.

METHOD OF DRYING BRICK AND TUNNEL THEREFOR.

Application filed April 23, 1927. Serial No. 186,108.

My present invention relates to the manufacture of brick and more particularly to an improved method of and apparatus for drying brick.

5 In the manufacture of brick, and particularly soft mud brick, an important and, at present, expensive operation is the partial drying of the brick prior to building the same into a kiln for burning. Various methods 10 have been devised for performing this necessary operation and numbers of pieces of apparatus have also been devised for this purpose. All prior methods and apparatus are so uneconomical as to be too expensive for the 15 ordinary brick plant and consequently this important operation is oftentimes neglected entirely and also is imperfectly done with the result that the loss from breakage is extremely high. In brick plants a large amount 20 of heat from furnaces and the like goes to waste annually and at the present time no efficient means or method is provided for utilizing this waste heat.

In my present invention I have devised an 25 improved method for drying brick and utilize the waste heat from the usual power plant of the yard. In carrying out my invention, I preferably employ a tunnel capable of holding any desired number of cars loaded with 30 pallets of brick, such tunnel preferably being associated with the smoke flue of the yard power plant and enclose such smoke flue in a chamber, such chamber having associated therewith power driven fans for creating a 35 circulation of air within the flue surrounding chamber, and for forcing such heated air into and around the brick in the tunnel.

The principal object of my invention, therefore, is an improved method of drying 40 brick.

Another object of my invention is an improved method of drying brick and a tunnel therefor.

45 Other objects and novel features of the construction and arrangement of parts comprising the improved tunnel will appear as the description of the invention progresses.

In the accompanying drawings illustrating the preferred embodiment of the tunnel 50 structure and by means of which my improved method may be carried out.

Fig. 1 is a plan view, partly in section;

Fig. 2 is an enlarged plan view of the right-hand end of the structure shown in

55 Fig. 1,

Fig. 3 is a sectional end elevation on the line 3—3 of Fig. 2, and

Fig. 4 is a longitudinal section on the line 4—4 of Fig. 3.

Referring to the drawings, 10 designates 60 an elongated tunnel provided with tracks 11 running longitudinally thereof, such tracks being spaced apart from each other and adapted to receive the supporting wheels 12 of a brick carrying car 13. The brick carrying car 13 substantially fills the height and breadth of the tunnel 10, as clearly shown in Fig. 3, and such brick carrying car is adapted to hold a plurality of super-imposed and parallelly arranged pallets 14, on which are 65 mounted the green brick to be dried. The tracks 11, as stated above, extend longitudinally of the tunnel 10 and are supported on a platform 15 constituting the floor of the tunnel and in this platform at intervals along 70 the length thereof are holes 16. The spacing between holes 16 is substantially equal to the space between the cars 13, so that, when the tunnel 10 is filled with cars, there will be a 75 hole 16 directly beneath each car. Adjacent 80 to the top 18 of the tunnel is a platform 17, this platform extending throughout the length of the tunnel and being provided with holes 20, similar in number and position to the holes 16. At the top of the tunnel is 85 formed an elongated chamber 19 divided into a plurality of sections by cross walls 20^a.

The inner wall of the tunnel 10 forms one 90 of the walls of a chamber 21 surrounding the smoke flue 22 of the power plant of the brick 95 yard. Adjacent to the top of the chamber 21 is a ceiling or wall 23 that forms the bottom plate of a rectangular chamber 24, the top 18 of the tunnel forming the top wall of such chamber. This rectangular chamber 24 100 extends parallel to the chamber 21 and the chamber 10 and the chamber 19 and communicates at intervals with the sections of the chamber 19 by transverse passages 25, for a purpose to be hereinafter described. The 105 bottom of the chamber 21 is formed of a floor 26 which is spaced apart from the ground and defines the upper wall of a longitudinal passage 27 that lies under and parallel to the chamber 21.

Beneath the floor 15 is an elongated chamber 2 which is divided into a plurality of sections by cross walls 3 and which communicates with the chamber 10 by holes 16. Also 110 said chamber 2 communicates with the outer 110

air by holes 4 and with the chamber 21 by holes 5.

Spaced apart from each other and from the chamber 21, but lying parallel to such chamber are a plurality of fans 28. The number of fans 28 may be any desired but for a dryer of the usual capacity I utilize preferably six fans. In speaking of the "usual capacity", the dryer chamber or tunnel 10 is made long enough to contain forty cars 13, and the cars 13 are of such length and capacity as to require a tunnel 13 of approximately 340 feet. Each fan 28 is provided with a discharge conduit 29 emptying into the longitudinal chamber 24, and from thence through the passages 25 into the sections of the chamber 19. The intake end of each fan 28 is connected by conduit 30 to the longitudinal chamber 21. Adjacent the entrance of each of the fans 28 is located a radiator 31 connected by suitable piping (not shown) to the exhaust steam pipe of the dryer plant.

Referring to Fig. 1, it will be noted that adjacent to the right-hand end of the tunnel 10 is an extension 33 provided on its top face with perforations 34 communicating with the outer air, and by means of which air is admitted to not only the portion 33, but with the end section of the chamber 2. This extension or portion 33 constitutes either a heating or cooling chamber, as may be desired. Preferably, however, this extension or portion 33 is used as a cooling chamber and the air passing through the perforations 34 passes over the heated bricks and cools said bricks down to atmospheric temperature and the heat thus extracted is passed on with the air and is utilized for drying the wet brick. This feature enables me to increase the speed at which the cars can be run through the dryer and also enables me to utilize a large amount of the heat which would be otherwise wasted.

Referring to Fig. 3 in connection with Fig. 1, the right-hand fan 28 takes heated air from the chamber 21—and indirectly from the auxiliary chamber 33—through the conduit 30 and forces such air through the outlet 29 into the chamber 24, through the passage 25, into the chamber 19. From the chamber 19, such air under light pressure passes through the orifices 20 and in a downward direction through the bricks stacked on the dryer cars 13 and thence downwardly through the orifices 16, from whence it passes into the chamber 21, coming in contact with the heated exhaust flue from the power plant. Air from the outside also passes through the holes 4 into the chamber 21. As it is necessary to add additional air at each section of the dryer, such air is admitted at atmospheric temperature through the openings 4. As the warm air leaving the tunnel 10, through openings 16, is practically saturated, the relatively cool outside air, coming in through the open-

ings 4, reduces the temperature of the saturated warm air to below the dew point and the moisture is thus extracted from the air and falls into a trough 15^a secured to a lower partition 15^b beneath the platform or floor 15 and this trough 15^a leads the moisture to any desired point. The second fan measured from right to left also working, will draw heated air from the chamber 21, which air passes through the conduit 30 over the heating pipes 31, through the second fan 28, the outlet 29, across the chamber 24, and through the passage 25, into the chamber 19 and from thence to the orifices 20 downward through the tunnel 10, the cars 13, the orifice 16 and into the chamber 21 again. This sequence of operations will be performed consecutively by each of the succeeding fans 28 measured from right to left and will, thus, in addition to causing a general flow of heated air from right to left in Fig. 1, will also cause practically a rotary motion of such heated air from the chamber 21 through the tunnel 10, and the air will pass from the extreme left-hand end of the chamber 21 or the tunnel 10 out into the open.

By reference to Fig. 4, it will be noted that the pallets 14 in the dryer car 13 are arranged in staggered relation to each other, this being obvious not only from the arrangement of pallets shown, but also from the lines indicating passage of air. This manner of placing the pallets causes the air to travel downward, as indicated, in a zigzagged course and each pallet of brick is exposed to the full current of air, thereby insuring more uniform and rapid drying.

By using the air a plurality of times and reheating the air after what might be termed each use or operation thereof, by means of waste heat from the power plant at the brick-yard, I am enabled to perform the drying operation on the bricks at a minimum cost and the apparatus by which I am enabled to do this is compact and relatively inexpensive to build and to maintain. In an apparatus of this kind where the smoke flue is approximately 340 feet to 350 feet long, and where the air utilized for drying the brick is repeatedly heated by the spent gases passing through the exhaust flue, a very economical way is obtained and the exhaust gases in their passage through the exhaust flue are reduced in temperature from approximately 550 degrees down to 200 degrees. This heat, therefore, which formerly has been wasted is utilized to good advantage in the drying of brick prior to building the same into a kiln.

Having thus described my invention, what I claim as new is:

1. An improved dryer for brick and the like comprising a tunnel open top and bottom, an air heating chamber arranged parallel thereto, means for heating said chamber, a plurality of blowers spaced apart from the tun-

nel, and connected thereto, said blowers being so arranged with respect to said tunnel and said heating chamber as to cause a downward movement of heated air through a plurality of points in a tunnel simultaneously and means for reheating the air prior to each downward movement.

2. That improved method of continuous drying of bricks which consists in forcing heated air downward through a line of bricks

at a plurality of points, and subjecting the heated saturated air after its passage through the brick to the cooling effect of cold air for the purpose of condensing the moisture therein and afterwards utilizing the partially dried and heated air together with the cold air to dry other bricks. ¹⁵

In testimony whereof, I have signed my name to this specification.

CLAUD E. FULLER.
